United States Patent Office.

APOLLOS RICHMOND, OF BROOKLYN, AND SAMPSON G. RICHMOND,
OF NORWICH, CONNECTICUT.

Design No. 3,346, dated January 19, 1869.

DESIGN FOR A STOVE.

The Schedule referred to in these Letters Patent and making part of the same.

To all whom it may concern:

Be it known that we, APOLLOS RICHMOND, of Brooklyn, in the county of Windham, and SAMPSON G. RICHMOND, of Norwich, in the county of New London, all in the State of Connecticut, have originated and produced a new Design for Parlor-Heating and Magazine-Stoves, of which the following is a full and clear description, reference being had to the accompanying drawing, making part of this specification.

Our design relates to the general form and surrounding of the top, and the style and construction of mouldings and edges of plates or castings of parlor-heater, magazine, and similar stoves.

The design consists of a beaded and framed moulding, cast upon the plate, as shown in the drawing, as also in the general design of the top and bottom plate, mica section, and shape of its different parts.

The drawing represents a photograph elevation of a stove embodying our design.

A denotes the base;

B, the mica section;
C, the top;
D, the open-work cover;
E C, mica panels;
F F, extreme bottom;
G G, the feet;
H, the top of base;
I, top of mica section; and
J, the bottom of mica section.

The further or general design of the stove will be readily understood from the drawing, without more detailed description.

We claim the design for the casting of parlor-heaters or magazine-stoves, as shown and described.

A. RICHMOND.
S. G. RICHMOND.
